UNITED STATES PATENT OFFICE

2,249,474

ELECTRIC TERMINAL

Claude A. Jagger and George H. Hamm, Schenectady, N. Y., assignors to General Electric Company, a corporation of New York

Application October 26, 1939, Serial No. 301,405

2 Claims. (Cl. 173—324)

Our invention relates to electric terminals, more particularly to detachable and adjustable terminals for edgewise wound resistors, and has for its object a simple, reliable and low cost terminal.

For a more complete understanding of our invention, reference should be had to the accompanying drawing in which Fig. 1 is a front elevation view partly in section of an electric resistor provided with a terminal embodying our invention; Fig. 2 is a side elevation view of Fig. 1; while Fig. 3 is a fragmentary side elevation view showing a modified form of our invention.

Referring to the drawing, we have shown our invention in one form as applied to an edgewise wound helical resistor comprising a supporting core 10 made of a suitable refractory, electrically insulating material, such as porcelain, and provided with a series of slots 11 and 12 on opposite edges to receive the turns of the edgewise wound resistor 13. Preferably, as shown, the resistor is a ribbon made of a suitable electrical resistance material, such as an alloy of nickel, chromium and iron.

In the operation of these resistors, it is desirable to have a terminal for the connection of the resistor in an electric circuit which terminal is adjustable or detachable so that it may be applied to a selected turn to include a larger or smaller amount of the resistor in the controlled circuit as desired. We provide a terminal 14 made of a suitable electrically conducting material, such as steel, which is clamped in place on a selected turn 15 by means of two transversely extending members, shown as screws 16 and 16a, and which may be removed by loosening these screws.

This terminal comprises a main body member 17 having an outwardly extending part 17a provided with a clamping screw 18 by means of which an electrical conductor can be secured thereto, and with two clamping projections 17b and 17c substantially on opposite sides of the support 10 and engaging one side of the resistor turn 15. Between the projections 17b and 17c, the material of the terminal is cut away, its outline being indicated in Fig. 1 by the dotted line 19; so that the lower edge of the terminal extends over and around the upper edge of the support 10, the terminal thus having a forked lower end.

Cooperating with these projections 17b and 17c are two small clamping members 20 and 21 through which the screws 16 and 16a extend to secure the members to the main body of the terminal. As indicated clearly in Fig. 2, these

members 20 and 21 engage the opposite side of the resistor turn 15 and the screws are tightened so as to clamp the resistor turn at points substantially diametrically opposite each other between the members 20 and 21 and the projections 17b and 17c. Thus two pairs of clamping projections 17b, 20 and 17c, 21 are provided. The upper end of each of the members 20 and 21 is bent over to form a laterally extending projection having a central narrow portion 22 extending through an aperture provided for it in the body member 14 and with a shoulder 23 on each side of the projection 22 which engages the body member. These shoulders space the upper end of each of the members 20 and 21 from the body member a distance 24 slightly greater than the thickness of the resistor turn 15 so that when the screws 15 and 16 are tightened, the members 20 and 21 are drawn flat against the side of the resistor turn. To accomplish this, the members 20 and 21 are sprung slightly toward the body member by the pressure of the clamping screws engaging the members 20 and 21 intermediate their ends. A rigid mechanical connection and a good electrical connection with the resistor turn at each point is thus assured.

Integral spacing projections 25 and 26 are also provided on the lower ends of the clamping members 20 and 21 respectively. As indicated in Fig. 1, the members 20 and 21 project toward the support 10 into the spaces at each side between the resistor coil and the support, the spacing projections 25 and 26 being bent laterally on the lower ends of these members in a direction parallel with the axis of the resistor coil so as to engage the inner edge of the turn at substantially diametrically opposite points of the turn. These projections thus definitely position the terminal in a direction away from the support and also position the projection 17b and 17c on each side at equal distances from the support. It will be observed that the projections 22 on the upper ends of the members 20 and 21 secure the clamping members against turning movement about the screws 15 and 16. Moreover, the screws themselves are situated just above the upper edge of the resistor turn and definitely fix the position of the terminal in the opposite direction, i. e., toward the support 10. Thus by loosening the screws 15 and 16 until the projections 25 and 26 slip by the resistor turn, the terminal can be easily removed.

In Fig. 3 we have shown a modified form of our invention in which an auxiliary clamping member 27 is provided which is in engagement with

the main terminal part 28. In this case the main terminal part does not have forked projections corresponding to parts 17b and 17c of Fig. 1, its lower edge being substantially straight across and these projections being formed by the separate part 27 through which the screw 29 on that side extends. The clamping member 30 on each side has substantially the shape of the members 20 and 21 of Fig. 1 although in this form of our invention, these parts 27 are preferably made of a thinner and spring material whereby close contact between these members and each side of the resistor turn is assured. At the top, the members 20 and 21 are each provided with a lateral projection 31 which extends through an aperture provided for it in the member 27 and, as before, through an aperture in the main terminal part 28.

While we have shown a particular embodiment of our invention, it will be understood, of course, that we do not wish to be limited thereto, since many modifications may be made and we, therefore, contemplate by the appended claims to cover any such modifications as fall within the true spirit and scope of our invention.

What we claim as new and desire to secure by Letters Patent of the United States is:

1. An electric terminal for an edge-wound ribbon resistor comprising a body member having a central upstanding portion provided with means for effecting an electric connection therewith, a pair of spaced clamping projections on the lower end of said member for engagement with one side of a turn of a resistor, a separate clamping member for each of said clamping projections, a screw for securing each of said clamping members to its clamping projection to clamp the sides of the resistor turn between them, said screw forming a stop for engagement with the outer edge of the resistor turn thereby to position said terminal inwardly on the resistor turn, a shoulder on the upper end of each of said clamping members engaging said clamping projection and spacing said clamping member from its clamping projection a distance somewhat greater than the thickness of the resistor turn so that when said screw is tightened said clamp-

ing member is bent somewhat to draw said clamping member flat against substantially the entire side of the resistor turn lying between said clamping member and said clamping projection, and a laterally extending positioning projection on the lower end of each of said clamping members extending across the inner edge of said turn to position said terminal outwardly on the resistor turn.

- 10 2. An electric terminal for an edge-wound ribbon resistor comprising a body member having a central upstanding portion provided with means for effecting an electric connection therewith, a pair of spaced clamping projections on the lower end of said member for engagement with one side of a turn of a resistor, a separate clamping member for each of said clamping projections, a screw for securing each of said clamping members to its clamping projection to clamp the sides of the resistor turn between them, said screw forming a stop for engagement with the outer edge of the resistor turn thereby to position said terminal inwardly on the resistor turn, each 15 20 25 30 35 40 45 of said clamping projections being provided with an aperture at its upper end on the side of said screw opposite the resistor turn, a laterally extending projection on the upper end of each of said clamping members projecting through said aperture thereby to position said clamping member on said clamping projection against turning movement about its screw, a shoulder on the upper end of each of said clamping members engaging said clamping projection and spacing said clamping member from its clamping projection a distance somewhat greater than the thickness of the resistor turn so that when said screw is tightened said clamping member is bent somewhat to draw said clamping member flat against substantially the entire side of the resistor turn lying between said clamping member and said clamping projection, and a laterally extending positioning projection on the lower end of each of said clamping members extending across the inner edge of said turn to position said terminal outwardly on the resistor turn.
